UNITED STATES PATENT OFFICE.

FERDINAND BECHOFF, OF SCHENECTADY, NEW YORK, ASSIGNOR TO GENERAL ELECTRIC COMPANY, A CORPORATION OF NEW YORK.

CIRCUIT-CONTROLLING MECHANISM.

1,037,580.

Specification of Letters Patent. Patented Sept. 3, 1912.

Original application filed December 16, 1908, Serial No. 467,881. Divided and this application filed January 24, 1910. Serial No. 539,649.

To all whom it may concern:

Be it known that I, FERDINAND BECHOFF, a subject of the Emperor of Germany, residing at Schenectady, county of Schenectady, State of New York, have invented certain new and useful Improvements in Circuit-Controlling Mechanism, of which the following is a specification.

My invention relates to electric switches and more particularly to switches which are used in systems of remote control and are interlocked to prevent the simultaneous closing of a plurality of control circuits, this application being a division of my application, Serial No. 467,881, filed December 16, 1908.

Many manually controlled devices, such as oil switches, must be installed in inconvenient and inaccessible locations and are usually operated by a remote control system in which a motor for operating the switch is controlled by means of control circuits leading from the motor to a conveniently located switch board.

Since the motor operated device is usually invisible from the switch board, the mechanism on the switch board for opening and closing the control circuits should not only be reliable, but should show the position of the motor actuated device, and the object of my invention is to provide a reliable and efficient controlling mechanism for opening and closing the control circuits in a reliable manner, for preventing the simultaneous closing of two or more control circuits and for indicating the position of the motor actuated device by showing which control circuit was last closed.

In carrying out my invention, a conveniently located switch board is provided with a switch for each control circuit and each switch has an indicator moved by it, the indicators of the switches being so related to each other that they interlock and thereby interlock the switches. In the preferred form, the switch remains closed only while held by the operator and is returned to the open position by a spring, a suitable connection between the indicator and switch permitting the indicator to remain in the position to which it was moved as the switch was closed, and thereby to show which switch was last closed. The positive and reliable closing of the control circuit is secured by mounting the coöperating contacts to make

sliding engagement with each other and at 55 the same time to be forced into contact with each other by a yielding pressure which increases as the contacts move over each other.

My invention will best be understood in connection with the accompanying drawing, 60 which is an illustration of one of the various forms in which the invention may be embodied, and in which—

Figure 1 is a plan view of the controlling mechanism mounted on the switchboard; 65 Fig. 2 is a view at right angles to Fig. 1, with part of the switchboard and of the mechanism broken away to show the construction; Fig. 3 is a plan view of the mechanism with the handles and upper plate removed to show the interlocking indicators; Fig. 4 is a plan view of the back of the switchboard with a portion of the mechanism broken away; Fig. 5 is an end view 70 partly in section showing the coöperating contacts in the position to close the control circuit, and Fig. 6 is a view similar to Fig. 5, with the contacts in the position to open the circuit.

The form of controlling mechanism shown 80 in the drawings is mounted on the switchboard or panel 1, to the rear of which is secured the back plate 2 and to the front of which is secured the front plate 3, the two plates being firmly held in position on the 85 switch board by means of binding screws 4, which pass through the switch board and connect the two plates. Operating handles 5 and 5^a are mounted on the front of the switch board on the front ends of rods or 90 switch actuators 6 and 6^a, which extend through both the front and back plates and through the switch board, as shown in Fig. 2. Each rod or switch actuator is loosely 95 journaled in the front and back plates to rotate and also to move longitudinally, so that each actuator is capable both of angular movement about its axis and of axial movement along its axis. The coöperating contacts for opening and closing the control 100 circuits are mounted behind the switchboard 1 and in the specific form of device shown in the drawings comprise movable contacts 7 and 7^a made in the form of bridging contacts mounted on and insulated from the 105 rods or switch actuators 6 and 6^a and coöperating with fixed contacts 8 and 8^a mounted on and insulated from the contact plate 2, as

shown in Fig. 4. The movable contacts 7 and 7^a are rotatable with the rods or switch actuators 6, 6^a and close the control circuit by bridging the gap between the fixed contacts, as shown in Fig. 5.

5 The control circuits may be both opened and closed by the operator, if desired, but in the preferred construction the control circuits are normally open and are closed only 10 so long as the handle is grasped by the operator. As shown in Figs. 2 and 3, the rods or switch actuators 6, 6^a are normally held in position to open the circuit by means of springs 9, 9^a connected at one end to the front 15 plate 3 and at the other end to the bosses 10, 10^a, mounted on the switch actuators between the front plate 3 and the switchboard. The springs are put under strain by the 20 rotation of the switch actuators to close the switches and as soon as the switch actuators are released by the operator, the springs draw the bosses back into engagement with the stops 11, 11^a, thereby opening the switches. The stops also prevent the 25 rotation of the switch actuators in the wrong direction. The two rods or switch actuators are interlocked and are prevented from simultaneously closing the switches by means of arms 12, 12^a on the bosses, which coöperate with arms 13, 13^a of movable indicators pivoted to the front plate 3 and provided with targets 14 and 14^a which register 30 with an opening 15 in the front plate 3 when the switch connected to the indicator is closed. Each indicator is actuated by the switch actuator to which it is connected and the indicators are interlocked with each other in any suitable way, preferably by being mounted to move in the same plane, 35 as shown in Figs. 2 and 3 and to overlap in said plane so that the indicators lie side by side and cannot be moved past each other. Each indicator is brought into registry with the opening 15 when its switch is closed, 40 but since the indicators overlap in the same plane, only one indicator can be in registry with the opening 15 at one time, and as long as it is in registry with the opening it blocks the movement of the other indicator and 45 thereby prevents the closing of the other switch. As shown in Fig. 3, the connections between the arms 12, 12^a on the bosses 10, 10^a and the arms 13, 13^a on the indicators are such that the switch actuator can be 50 turned back to switch opening position without drawing the indicator back with it, and thereby moving the indicator out of registry with the opening 15. The indicators move with enough friction to prevent displacement, 55 and when either indicator has been brought into registry with the opening 15, it remains in registry with the opening until displaced by the other indicator when the other switch is closed. It is impossible to 60 bring both switches into the switch closing 65

position at the same time, since both indicators cannot be brought into registry with the opening 15 at the same time, and neither switch is closed until its indicator is in registry with the opening 15.

The coöperating contacts 7, 7^a and 8, 8^a for closing the circuits are brought into firm and reliable engagement with each other by sliding over each other as the switch is closed and also by being forced into yielding engagement with each other with a pressure which increases as the contacts slide over each other. The preferred construction for securing this result is shown in the drawing, in which angular movement of the switch actuator about its axis causes its axial movement in a direction to force the movable contact into firm engagement with the fixed contacts. The preferred construction for securing this movement of the switches comprises resilient helical abutments, preferably in the form of helical springs 16, 16^a, surrounding the switch actuators 6, 6^a and each having one end secured to the back plate 2. The movable contacts 7, 7^a are operatively connected to the resilient supports or abutments 16, 16^a by means of lugs or pins 17, 17^a mounted on the switch actuators and engaging the helical springs between the ends. As shown in Figs. 5 and 6, the helical spring forms a yielding screw thread which coöperates with the pin 17, 17^a to move the switch actuators longitudinally, thereby forcing the movable contacts into yielding engagement with the fixed contacts. As the movable contact is rotated while in engagement with the fixed contacts, the helical spring is compressed more and more and the pressure exerted between the contacts increases as the contacts slide over each other, thereby insuring a positive and reliable closing in the control circuit.

My invention may be embodied in many other forms from that shown and described and I therefore do not wish to be restricted to the precise arrangement disclosed, since various modifications and changes may be made without departing from the spirit of my invention.

What I claim as new and desire to secure by Letters Patent of the United States, is:—

1. The combination with coöperating contacts mounted to rotate in sliding engagement and to move one toward the other, of means whereby one of said contacts is yieldingly pressed upon the other with a pressure dependent upon the extent of their relative rotation when in engagement.

2. The combination with coöperating contacts mounted to rotate in engagement and to move one toward the other, of a resilient member arranged to force one of said contacts toward the other when strained, and means whereby rotation of one of said contacts strains said resilient member to an ex-

tent dependent upon the extent of movement of one of said contacts over the other.

3. The combination with a fixed contact and a coöperating movable contact mounted to rotate in sliding engagement with and to move toward said fixed contact, of a resilient helical member mounted with one end in fixed relation to said fixed contact and arranged to coöperate with said movable contact to cause said movable contact to move in a spiral path toward the fixed contact as said movable contact is rotated.

4. The combination with a fixed contact and a coöperating movable contact mounted to rotate in sliding engagement with and to move toward said fixed contact, of a helical spring fixed at one end relatively to said fixed contact and concentric with the axis of rotation of said movable contact, and connections between said movable contact and said spring whereby the rotation of said movable contact causes said contact to be moved by said spring toward said fixed contact.

5. The combination with relatively movable coöperating contacts, of a rotatable actuator mounted to move axially and thereby bring said contacts into engagement, and a resilient member having an inclined surface engaged by said actuator to move said actuator axially and thereby bring said contacts into yielding engagement when said actuator is rotated.

6. In a switch, the combination with relatively movable coöperating contacts, of an actuator mounted for angular and longitudinal movement and arranged to bring said contacts into engagement when moved longitudinally, a helical spring surrounding said actuator and having one end fixed with relation to one of said contacts, and a projection on said actuator in engagement with said spring between its ends, whereby rotation of said actuator brings said contacts into yielding engagement.

7. In a switch, the combination with relatively movable coöperating contacts, of an actuator mounted for angular and longitudinal movement and arranged to bring said contacts into engagement when moved longitudinally, a resilient abutment mounted adjacent said actuator and having an inclined portion at an angle to both directions of movement of said actuator, and a projection on said actuator in engagement with the inclined portion of said abutment.

dinal movement and arranged to bring said contacts into engagement when moved longitudinally, a resilient abutment mounted adjacent said actuator and having an inclined portion at an angle to both directions of movement of said actuator, and a projection on said actuator in engagement with the inclined portion of said abutment.

8. The combination with relatively movable coöperating contacts, of an actuator for said contacts, a helical spring surrounding said actuator, said spring and said actuator being mounted for both angular and longitudinal movement relatively to each other and arranged to bring said contacts into engagement by relative longitudinal movement, and a projection on said actuator in engagement with said spring between its ends, whereby relative angular movement of said spring and actuator produces relative longitudinal movement thereof.

9. In a switch, the combination with a fixed contact and a coöperating movable contact mounted for angular and axial movement relative to said fixed contact, of a stationary helical resilient abutment for said movable contact, and connections between said abutment and said movable contact whereby angular movement of said movable contact relatively to said abutment causes said contact to move axially into yielding engagement with said fixed contact.

10. In a switch, the combination with a fixed contact and a coöperating movable contact mounted for angular and longitudinal movement relative to said fixed contact, of a stationary helical spring surrounding the axis of rotation of said contact, and a pin on said contact in engagement with said spring between its ends, whereby rotation of said movable contact brings it into yielding engagement with said fixed contact.

In witness whereof, I have hereunto set my hand this 21st day of January, 1910.

FERDINAND BECHOFF.
